US00D936967S

(12) United States Design Patent (10) Patent No.: US D936,967 S
(45) Date of Patent: * Nov. 30, 2021

(54) PACKING CASE

(71) Applicant: Workplace-Worksafe Limited, Ruthin (GB)

(72) Inventor: Rhian Parry, Ruthin (GB)

(73) Assignee: Workplace-Worksafe LTD, Ruthin (GB)

() Term: 15 Years

(21) Appl. No.: 35/509,674

(22) Filed: Dec. 20, 2019

(80) Hague Agreement Data

Int. Filing Date: Dec. 20, 2019

Int. Reg. No.: DM/206731

Int. Reg. Date: Dec. 20, 2019

Int. Reg. Pub. Date: Jun. 26, 2020

(51) LOC (13) Cl. 03-01

(52) U.S. Cl.

USPC D3/273

(58) Field of Classification Search

USPC D9/414, 420, 423, 424, 430, 432, 654, D9/428, 455; D3/272, 273, 276, 282,
